Inventor

Harold M. Plaisted,

Patented Nov. 17, 1925.

UNITED STATES PATENT OFFICE.

HAROLD M. PLAISTED, OF ST. LOUIS, MISSOURI.

ROTARY PIVOTED HAMMER.

Application filed February 23, 1923. Serial No. 620,676.

To all whom it may concern:

Be it known that I, HAROLD M. PLAISTED, a citizen of the United States, residing at St. Louis, State of Missouri, have invented 5 certain new and useful Improvements in Rotary Pivoted Hammers, of which the following is a specification.

This invention relates to certain new and useful improvements in rotary pivoted hammers for crushers and pulverizers for use with coal, shale, grain or other material, the 10 peculiarities of which will be hereinafter fully described and claimed.

The main object of my invention is to 15 provide a rotary pivoted hammer with an adjustable cutter block adapted to present eight cutting edges in succession as the operative edge and fully protect from wear all edges except the one in operative position; secondly, to form the cutting edges on 20 said block so as to maintain a sharp cutting edge while being worn down; and thirdly, to mount such a block detachably, yet securely in the head of the hammer.

25 In the accompanying drawing on which like reference numerals indicate corresponding parts, Fig. 1, represents a front view of a hammer exemplifying my invention; Fig. 2, a side view of the same; Fig. 3, a rear view; Fig. 4, a detail front view of the 30 cutter block; and Fig. 5, a section on the line 5—5 of Fig. 4.

1 designates the shank of a rotary pivoted hammer having an eye 2 at one end for 35 pivotal mounting as usual, and having a head 3 considerably thicker than the shank 1 as shown in Figs. 1 and 3. In this head is formed a recess 4 dividing the head into two jaws 6 and 7,—the former being shorter than the rear jaw 7. In this recess is 40 mounted a cutter block, 23, preferably cruciform as viewed from the side, Fig. 2, and consisting of four radiating arms 8, 9, 10, and 11 formed by cutting away portions of 45 the block as indicated in Fig. 5. The sides of said arms are preferably curved so as to make acute angles with the ends of the arms as shown in Figs. 2 and 5. The sides of the arms may be otherwise than curved if desired, but the preferred form allows of still 50 presenting a sharp cutting edge as the operative edge is worn down in the reduction of material. The sides of the arm are adapted to constitute bearing surfaces to support 55 the block in the recess, and said recess has

matching bearing portions preferably three, designated 12, 13 and 14, adapted to be engaged by a corresponding number of the eight bearing surfaces at the side of said arms, whatever the adjustment of the block 60 by rotating and reversing the same. The non-bearing portions of the recess allow play for readily assembling the block and head.

The front jaw is shorter than the rear 65 jaw so as to expose the outer cutting edge 22 of the block and adjacent throat, to the material being reduced, and still protect the next forward cutting edge of the block from wear by the material. The rear jaw backs 70 up the outer cutting edge in operation, and also protects the next adjacent rear edge of the block with which it is practically even or flush as shown.

75 Means for securing the block detachably in the recess are provided, preferably a bolt 15 mounted in the head 3 inclined to the radial axis X through the pivot and center of gravity of the hammer, and extending through the block diagonally by means of 80 16 and 17 Fig. 5, that cross each other at the center of the block, and are enlarged to sink the head of the bolt as shown in Fig. 2. A nut 18 on the threaded end of the bolt, or other fastening 85 means for the bolt, allows of drawing the cutter block down against the bearing portions of the recess so as to engage the adjacent bearing surfaces of the block. A spring 90 washer 19 of leather or other suitable material, is compressed by the nut 18 against a boss 20 at the back of the head, and a cotter 21 prevents its turning off. The bolt preferably passes through the bearing portion 13 and the bearing surface of the arm engaged thereby, and is intermediate of the bearing portions 12 and 14 so that the block is held firmly yet detachably.

95 The cutting edges of the block are equidistant from the center as indicated in Fig. 5, and the radial axis Y of the recess is inclined backward from the direction of rotation so as to bring the outer front edge 22 further from the central axis of the pivot 100 than the adjacent rear edge of the same arm. This edge 22 is the operative edge in the adjustment of the block shown, and all the other cutting edges are hidden by the jaws 7 and 8 and the recess, so that they are protected from wear. Each edge however may 110

be readily adjusted to the position of the edge 22 and become in succession the operative edge, until all the edges are worn down. The bearing portions of the recess engaging 5 the side bearing surfaces of the arms bring each cutting edge in succession to the same operative position and the fastening means, such as the bolt passing through the cross passages 16 and 17, hold the cutter block 10 securely yet detachably in the head.

This hammer is pivotally mounted in multiple in any suitable manner to form a rotor in a casing, such as on rods in perforated discs mounted on a rotor shaft as 15 shown in my prior Patent No. 1,413,611, dated April 25th, 1922.

I claim:

1. A rotary pivoted hammer comprising a shank adapted for pivotal mounting and 20 having a solid head with a recess having three bearing portions, a cutter block adjustably mounted in said recess and having eight operative edges,—said head being adapted to protect from wear all edges except the one in operative position, and said block having eight bearing surfaces, three of which engage said bearing portions of the recess in each adjustment of the block,— 25 and means detachably securing said block 30 in said recess.

2. A rotary pivoted hammer comprising a shank adapted for pivotal mounting and having a solid head with a recess having three bearing portions, a cutter block adjustably mounted in said recess and having 35 eight operative edges,—said head being adapted to protect from wear all edges except the one in operative position, and said block having eight bearing surfaces, three 40 of which engage said bearing portions of the recess in each adjustment of the block, a bolt passing through said block and head at one bearing portion of the recess intermediate of the other two, and fastening 45 means for said bolt.

3. A rotary pivoted hammer comprising a shank adapted for pivotal mounting and having a solid head with a recess having bearing portions, a cutter block adjustably 50 mounted in said recess and having bearing surfaces successively matching said bearing portions of the recess,—said block having reentrant cutaway portions forming eight edges adapted to form successively the operative edge while the others are hidden in 55 said recess, and having through passages crossing each other and connecting opposite cutaway portions, and fastening means adapted to be mounted in said head and one 60 of the through passages of said block successively and intermediate of the bearing

portions of the recess and their corresponding bearing surfaces of the block.

4. A rotary pivoted hammer comprising a shank adapted for pivotal mounting and 65 having a solid head with a recess forming a front jaw and a longer rear jaw, a cruciform cutter block with multiple cutting edges adjustably mounted in said recess and having only its front operative edge exposed by the front jaw and located further from the pivot than the other cutting edges, and means adjustably securing said block in 70 said recess.

5. A rotary pivoted hammer comprising 75 a head having a shank adapted for pivotal mounting, a cruciform cutter block mounted in said head and having eight cutting edges equidistant from the center of the block, a head on said hammer having a recess in one side receiving said block mounted therein and covering all but the outer front one of said edges,—the head being provided with a shank adapted for pivotal mounting, and the radial axis of the recess 80 being inclined backward so that the exposed operative edge is at a greater distance from the pivot than the adjacent rear edge of the block.

6. A rotary pivoted hammer comprising 85 a head having a shank adapted for pivotal mounting, a cruciform cutter block mounted in said head and having eight cutting edges equidistant from the central axis of the block, the side surfaces of the arms of 90 the cross being curved and forming an acute angle with the end surfaces of the arms making sharp cutting edges, and adapted to be fastened in said hammer.

7. A rotary pivoted hammer comprising 95 a head having a shank adapted for pivotal mounting, a cruciform cutter block mounted in said head and provided with eight cutting edges,—the central portions of the block having two through passages crossing each other in the center and connecting 100 opposite cutaway portions, substantially as shown and for the purpose set forth.

8. A rotary pivoted hammer comprising a shank adapted for pivotal mounting at 110 one end and provided with a solid head having a recess at its outer end and on one side dividing it into outwardly projecting jaws,—the front jaw being shorter than the rear jaw,—a cutter block mounted in said recess and exposing one cutting edge beyond the front jaw, and means detachably securing said block in the head.

In testimony whereof I have affixed my signature.

HAROLD M. PLAISTED.
